TOBACCO PIPE

Filed July 15, 1936

INVENTOR:

JOSEPH PEDERY
Benjamin Yonan
ATTORNEY.

UNITED STATES PATENT OFFICE

2,204,282

TOBACCO PIPE

Joseph Pedery, New York, N. Y.

Application July 15, 1936, Serial No. 90,622

3 Claims. (Cl. 131—206)

This invention relates to improvements in tobacco pipes. The draught or suction of such pipes is frequently impaired through the clogging which takes place at the bottom of the pipe bowl, and particularly at the junction of the bowl and the pipe stem, which clogging is due to continual accumulation of various ingredients distilled out of the tobacco during the smoking. Those accumulated ingredients have to be frequently scraped out of the bowl, as, besides impairment of the suction, they also form hard or viscous masses which seriously vitiate the taste of the tobacco.

The principal object of the invention is to provide a tobacco pipe with improved and efficient means for remedying the above mentioned disadvantages, to ease the conveyance of the smoke through the pipe, and to prevent the distilled objectionable ingredients of the tobacco from reaching the smoker's mouth.

Another object is to provide a tobacco pipe having simplified, inexpensive, reliable, efficient, and improved means for retaining an absorbent material for remedying said disadvantages, and for readily, rapidly, and conveniently discarding and renewing said material.

A further object is to effect the improved distillation of objectionable ingredients from the tobacco within the pipe.

A still further object is to provide improved means for gaining access to all the parts and surfaces in the region of the junction of the pipe bowl and stem, for the rapid, convenient, and efficient cleaning of the same.

A still further object is to provide improved means for maintaining the pipe stem in clear state.

Other objects and advantages will hereinafter appear.

In the accompanying drawings,

Fig. 1 is a longitudinal cross-sectional elevation of a tobacco pipe embodying the above referred improvements, and showing same as applied to a corn cob form of tobacco pipe.

Fig. 2 is a similar type view illustrating a modification of the improvements shown in Fig. 1.

The pipe 1, Fig. 1, comprises a bowl 2 of corn cob type and stem 3, the former having its bore 4 extending clear therethrough, from the rim 5 to the bottom 6. The upper or fire-pot portion of said bore has its wall 7 tapering downwardly, then the wall continues vertically for a comparatively short distance, as shown at 8, from there it again tapers for a short distance at 9, then it continues vertically as at portion 10, and from

the latter the wall continues to the bottom as a narrower bore portion 11. In the bore-portion 10 is removably seated a fitting 13 comprising a flange 14 serving as a floor for the fire-pot 7. Upon ribs 15 of flange 14 is seated a tablet 19 made of any suitable material which will absorb objectionable ingredients from the burning tobacco. Said tablet is of frusto-conical configuration as shown, having a cavity 20 thereunder, and a plurality of smoke conducting passageways 21 are formed in the periphery of the tablet. A cap 22 having a cavity 23 slides upwardly into the bore 11, thereby sealing said bore at the underside 6 of the bowl 2 and forming a chamber out of the bore-portion 11. There is provided a bored post 27 which is molded as shown in the cap 22 and it threads at 28 clear through the fitting 13, whereby all these parts are efficiently held together and to the bowl 2, and may be conveniently separated and reassembled for cleansing purposes. Openings 29 connect the bore 18 of post 27 with the chamber 11. The cap 22 is preferably provided with a gasket 30 to insure an air and smoke-tight fit against the underside 6 of the corn cob bowl 2. In the terminal 24 of stem 3 is removably fitted a tube 25 which projects into the chamber 11 and is located above the cavity 23.

The tablet 19 is so dimensioned at its top-most or largest diameter that it fits snugly when passed through the straight-walled portion 8 of the bore when inserted in the operative position shown, in which position it is consequently securely retained against dropping out during handling of the pipe when it is not smoked. As the pipe is used, the absorbent tablet 19 may be regularly renewed as it becomes worn by merely breaking it, casting out the pieces, and reinserting a fresh tablet in the above described manner, the arched cavity 20 facilitating the demolishing of the tablet. While the pipe is being smoked the tablet 19 absorbs certain of the objectionable ingredients of the tobacco, and the smoke is conducted through its passageways 21, over the flange 14 and between ribs 15 of fitting 13, upwardly into cavity 20, downwardly through the bore 18 of post 27, through the openings 29, into the chamber 11, and through tube 25 into the stem 3. During said passage of the smoke certain viscous objectionable ingredients not absorbed by the tablet 19 will be trapped in the spaces between the ribs 15, and others not so trapped, such as solids, will be carried through the bore 18 and the openings 29, and drop into the cavity 23 and therein deposited. As smokers often cause their saliva to enter the stem, the

same will be emitted through the tube 25 and likewise drop into the cavity 23. The spaces above flange 14 between ribs 15 may be occasionally cleaned out of its collected matter, and the receptacle 23 may be also conveniently cleaned out by merely unthreading the post 27 and thereby removing the cap 22.

In the pipe shown in Fig. 2, a grate 45 is seated upon an annular shelf 46 formed in the wall of the bore 4, and a bolt 47 molded in the cap 22 threads into a tapped opening 48 in the grate, whereby said parts may be disassembled and reassembled as required, and functioning in the above described manner. The end portion 49 of the stem-tube 25 is disposed obliquely and toward the receptacle 23, to facilitate exudation of any saliva being emitted from the stem 3 and depositing it directly into said receptacle.

Having thus described my invention, I claim:

1. In a tobacco pipe, the combination with a bowl and stem, said bowl having a perforated floor, a tablet of absorbent material located above said floor having a downwardly tapering wall, and the interior of said bowl having a vertical wall

portion of a diameter corresponding to that of the top area of said tablet, a wall portion tapering downwardly from said vertical portion, and a wall portion tapering upwardly from said vertical portion, to insure a wedging fit of said tablet in said bowl.

2. In a tobacco pipe, the combination with a bowl and stem, said bowl having a floor with a tapped opening therein, said floor having a chamber thereunder extending clear through the bottom of the bowl, a cap carrying a threaded tube, attachable to and detachable from said tapped opening, the bore of said tube leading to said chamber, and said stem leading to said chamber.

3. In a tobacco pipe, the combination with a bowl and stem, said bowl having a floor with a tapped opening therein, said floor having a chamber thereunder extending clear through the bottom of the bowl, a cap for opening and closing the bottom of the bowl and said chamber, said cap carrying a post extending from it and having a terminal threading into and out of said opening, and said stem leading to said chamber.

JOSEPH PEDERY.
